UNITED STATES PATENT OFFICE.

GEORGE HENRY RICKE, OF CINCINNATI, OHIO, ASSIGNOR, BY DIRECT AND MESNE ASSIGNMENTS, TO SAMUEL K. DRUCE, JOHN ASA HOSBROOK, AND DANIEL S. HOSBROOK, OF MADEIRA, OHIO.

HANGER-CLAMP FOR TROLLEY-WIRES.

SPECIFICATION forming part of Letters Patent No. 674,656, dated May 21, 1901.

Application filed December 28, 1900. Serial No. 41,388. (No model.)

To all whom it may concern:

Be it known that I, GEORGE HENRY RICKE, a citizen of the United States of America, and a resident of Cincinnati, in the county of Hamilton and State of Ohio, have invented certain new and useful Improvements in Hanger-Clamps for Trolley-Wires, of which the following is a specification.

This invention relates to certain improvements in wire-clamps such as are employed for holding trolley-wires and the like; and the object of the invention is to provide a device of this character of a simple and inexpensive nature and of a strong and durable construction having improved devices adapted for securely clamping and holding the wire, while permitting of ready operation to release the wire, so as to facilitate repairs.

The invention consists in certain novel features of the construction, combination, and arrangement of the several parts of the improved wire-clamp whereby certain important advantages are attained and the device is made simpler, cheaper, and is otherwise better adapted and made more convenient for use, all as will be hereinafter fully set forth.

The novel features of the invention will be carefully defined in the claims.

In the accompanying drawings, which serve to illustrate my invention, Figure 1 is a side view showing a wire-clamp embodying my invention, and Fig. 2 is a central sectional view taken transversely and vertically through the improved wire-clamp. Fig. 3 is a view showing the inner surface of one of the clamping parts or members detached. Fig. 4 is a view showing the upper threaded ends or shanks of the clamping members and the nut for holding them in relation.

As shown in the views, the improved wire-clamp comprises two similar clamping parts or members having laterally widened or expanded portions 2 at their lower ends, said widened portions forming clamping-jaws 45 adapted to impinge upon opposite sides of the trolley-wire, (indicated at α in Figs. 1 and 2,) the clamping-jaws 2 having on their inner surfaces longitudinal grooves or channels 3, conforming to the lateral curvatures of the 50 trolley-wire α , so as to permit said jaws when

pressed tightly together to securely clamp and hold the said wire between them.

The parts or members 1 of the wire-clamp are formed on their outer surfaces with centrally-located strengthening or stiffening ribs 55 4, which extend down to the lower parts of the clamping-jaws 2, and the upper portions of said members 1 are thickened to form shanks 5, which are each made of semicircular cross-section and are adapted to fit together when the two parts or members of the clamp are assembled to produce a tubular part, as shown in Figs. 2 and 4, which part is formed with exterior screw-threads 6 to enable it to be screwed into a nut 7, herein 65 shown as formed with a hexagonal upper part adapted to receive a wrench or other tool whereby it may be conveniently turned.

The hollows of the shanks 5 when the parts or members 1 of the clamp are assembled correspond one with the other and form a socket 8, which is provided with interior screw-threads 8' and is adapted to receive the threaded end of a bolt 9, having a head 11 at its upper end. The improved wire-clamp is suspended by 75 means of said bolt, an insulator 10 being held upon the bolt in a well-known way.

The screw-threads 6 are not extended the entire lengths of the shanks 5, but run from the upper ends part way down said shanks, 80 and at their lower ends the said screw-threads are made shallower, as shown at 12 in Figs. 2 and 3, so that when the nut 7 is screwed down upon the said screw-threads and comes into engagement with the shallower portions 85 12 thereof the nut will exert a wedging action upon the parts or members 1 of the clamp and will force the said parts or members one toward the other.

The inner surfaces of the parts or members 90 1 are extended in substantially parallel planes, as seen at 14 in Fig. 2; but said surfaces are spaced apart one from the other and are formed at their edge portions with projecting strengthening ribs or flanges 13, and said 95 flanges or ribs extend at angles to the surfaces whereon they are formed, being made to fit flush upon each other at the upper parts or shanks of the members and being gradually spaced apart from each other to- 100

ward the lower portions of the members, the flanges or ribs merging in the surfaces 14 at the grooves or channels 3, as shown in Figs. 2 and 3. By this means it will be seen that 5 as the nut 7 is turned and screwed down upon the shanks 5 of the clamping members and comes into engagement with the shallower portions 12 of the screw-threads 6 on said shanks the space between the flanges or ribs 10 13 at the lower portions or clamping-jaws 2 of the members will permit the said lower portions or jaws to be pressed by the wedging action of the nut forcibly upon the opposite sides of the trolley-wire α , so as to securely 15 clamp and hold the said wire. The socket 8, formed in the upper parts 5 of the members, also affords a convenient means to receive the bolt or other part by means of which the improved wire-clamp is suspended.

20 From the above description it will be seen that the improved wire-clamp is of an extremely simple and inexpensive nature and affords a secure means for holding the trolley-wire, while permitting of its being readily 25 actuated by merely unscrewing the nut 7 to release the wire from the clamping engagement of the jaws 2 therewith, so that repairing is greatly facilitated. When desired, also, the clamping members 1 may be readily 30 disengaged from the nut 7 and replaced with little difficulty. It will also be obvious from the above description of my improvements that the improved wire-clamp is capable of some modification without material departure from the principles and spirit of the in- 35

vention, and for this reason I do not wish to be understood as limiting myself to the precise form and arrangement of the several parts of the device herein set forth.

Having thus described my invention, what 40 I claim, and desire to secure by Letters Patent, is—

1. In a wire-clamp, the combination of members having clamping-jaws to impinge upon a wire and formed with hollows adapted 45 to correspond, when the members are held in relation, to produce a socket the walls of which are screw-threaded, a part having wedging and screw-threaded engagement with the outer sides of said members to press 50 said jaws forcibly upon the wire, and a bolt having at its lower end threaded engagement in said socket, substantially as set forth.

2. In a wire-clamp, the combination of members having clamping-jaws to impinge 55 upon a wire and having strengthening flanges or ribs upon their inner surfaces, said flanges or ribs being spaced apart adjacent to the clamping-jaws and being fitted flush one on the other at the other end of the wire-clamp 60 and a part having wedging engagement with the outer sides of the members to press said jaws forcibly upon the wire, substantially as set forth.

Signed at Cincinnati, Ohio, this 24th day of 65 December, 1900.

GEORGE HENRY RICKE.
